(57) **CLAIM**

The ornamental design for a transformable toy figure, as shown and described.

DESCRIPTION

FIG. 1 is a front perspective view of a transformable toy figure showing my design in a first, untucked position;

FIG. 2 is a front elevation view of the transformable toy figure in the first position;

FIG. 3 is a left side elevation view of the transformable toy figure in the first position;

FIG. 4 is a right side elevation view of the transformable toy figure in the first position;

FIG. 5 is a rear elevation view of the transformable toy figure in the first position;

FIG. 6 is a top plan view of the transformable toy figure in the first position;

FIG. 7 is a bottom plan view of the transformable toy figure in the first position; and,

FIG. 8 is a front elevation view of the transformable toy figure showing my new design in a second, tucked position.

The transformable toy figure parts shown in broken lines in FIG. 1 is shown for illustrative purposes only and form no part of the claimed design.
